CARBURETOR SUPPLEMENTARY FUEL FEED
DEVICE WITH AUXILIARY FUEL PUMPDavid E. Anderson, Cleveland, Ohio, assignor to
Thompson Products, Inc., Cleveland, Ohio, a
corporation of Ohio

Application May 27, 1949, Serial No. 95,829

2 Claims. (Cl. 261—34)

1

This invention relates to devices for feeding controlled amounts of coolant or anti-detonant fluid to the fuel intake of an internal combustion engine. Specifically, this invention has to do with an anti-detonant fuel feeding device featuring, in addition to the usual vacuum operated supplementary feed device, an auxiliary pump which acts only during a condition of very low vacuum to feed an extra, metered quantity of anti-detonant fuel to the fuel intake of the engine.

It is known in the art that engine detonation varies with compression ratio, the quality and type of fuel being burned, and the load on the engine. Likewise, the feeding of supplementary fuels, such as water, alcohol, and the like, to internal combustion engines for power output of the engine is known. It is also known that during smooth running periods of the engine the intake manifold vacuum is relatively high. However, when the engine is rapidly accelerated or a load is suddenly put on the engine, the intake manifold pressure will rapidly increase and very low vacuum conditions will exist, whereupon the engine will tend to knock. Upon occurrence of such a low vacuum condition, in order to prevent such knocking, the device of the present invention will quickly act to inject an extra charge of anti-detonant fluid to supplement any anti-detonant feed then being added to the engine.

Accordingly, there is provided in this invention an auxiliary feed device including a housing defining an upper vacuum chamber and a lower vacuum chamber in flow communication with each other and with a source of vacuum. A float controlled fluid storage chamber is disposed in the housing between the upper and lower vacuum chambers and is in flow communication with a discharge conduit leading to the fuel intake passage of the engine.

A spring-pressed diaphragm is disposed in the upper vacuum chamber and is arranged, in the usual manner, to close a control valve in the conduit between the float chamber and the engine fuel intake in response to increasing vacuum in the upper vacuum chamber. A second diaphragm is disposed in the lower vacuum chamber and is arranged to flex against the compression of a spring as the vacuum in this lower chamber is increased.

This second diaphragm divides the lower chamber into a vacuum chamber and a fluid storage compartment which is supplied with fluid from the float chamber. A pair of ball-type check valves maintain a predetermined quantity of fluid above the diaphragm in the storage compartment

2

which also has a passageway leading to the fuel inlet of the engine.

Thus, if the engine intake manifold has attained a high vacuum condition running, for example, at half throttle, the high vacuum in the upper vacuum chamber would draw the diaphragm therein downwardly to close the metering valve and prevent the discharge of further supplementary anti-detonant fluid to the engine.

10 In this high vacuum running condition the engine does not need a supplementary anti-knock fluid. In the lower vacuum chamber this high vacuum condition will draw the diaphragm into a cocked position against the compression of the spring.

15 Now, if the engine is suddenly accelerated to full throttle, a low vacuum condition will occur in the engine intake manifold, and the diaphragm in the upper chamber will be actuated by the compressed spring to open the metering valve and permit supplementary anti-knock fluid to be drawn into the engine fuel intake. In the lower vacuum chamber the coiled spring will actuate the diaphragm upwardly to force a predetermined quantity of supplementary anti-detonant fluid into the engine.

20 Thus, there is provided in this invention an auxiliary, vacuum-actuated diaphragm effective under sudden low vacuum conditions to discharge a jet of anti-detonant fluid into the intake passage of the engine to supplement the anti-detonant fluid being normally supplied under low vacuum conditions by the usual supplementary fuel feed device.

25 Accordingly, it is an object of this invention to provide a supplementary fuel feed device arranged to not only supply anti-knock fluid to an engine in response to intake manifold conditions, but to inject an additional quantity when sudden low vacuum conditions are encountered.

30 Another object of this invention is to provide, in an anti-detonant fuel feed device, a supplementary vacuum controlled chamber that, by means of a calibrated spring, may be arranged to supply an additional quantity of fluid only after a predetermined minimum drop in vacuum pressure in the engine manifold.

35 Other and further features, advantages and objects of the present invention will become apparent to one skilled in the art from the following detailed description taken in connection with the accompanying drawings.

On the drawings:

Figure 1 is a vertical central sectional view 50 of a fuel feed device constructed according to

the teachings of the present invention, shown connected to the carburetor of an engine;

Figure 2 is a central vertical sectional view similar to Figure 1 but showing the mechanism of this feed device in a different operating position;

Figure 3 is a top plan view of the device of Figure 1; and

Figure 4 is a horizontal sectional view taken on line IV—IV of Figure 2.

As shown on the drawings:

In Figure 1 the reference numeral 10 designates generally a supplementary feed device constructed according to the teachings of this invention and mounted by means of flange or mounting block 11 which is attached to a carburetor 12. The block 11 carries passageways 13 and 14 receiving tubular nozzles 15 and 16, respectively, which extend into the Venturi openings of the carburetor. As seen in Figure 3 and 20 in Figure 4, the carburetor 12 is a dual carburetor and therefore two sets of nozzles 15 and 16 are provided on this feed device. As is customary, fuel feed from the carburetor is controlled by a throttle valve 18.

The device 10 includes a main body portion 20 having a recess 21 in the upper surface thereof with a cover member 22 suitably secured across said recess. A flexible diaphragm 24 is secured at its marginal edges between the body 20 and the cover 22 and extends across the recess 21 defining an upper chamber 25 vented to atmosphere by a vent hole 26 in the cover and a lower vacuum chamber 27 connected by a fitting 28 (Figure 3), a tube 29 and a fitting 30 (Figure 1) to the fuel inlet passage 32 of the engine.

A cup-shaped lower casing portion 33 is held in sealed engagement with the body 20 with a gasket 34 of resilient material therebetween by means of a plurality of cap screws (not shown).

The lower surface of the casing portion 33 has a recess 36 which is enclosed by a closure plate 37 secured to the casing 33 by any suitable means.

A diaphragm 39 is disposed across the recess 36 having marginal edges secured between the casing 33 and the closure plate 37. The diaphragm, in connection with the casing 33 and the closure plate 37, defines an upper fluid storage compartment 41 and a lower vacuum chamber 42 which is in communication with the upper vacuum chamber 27 by means of a passageway 43 in the closure plate 37, an aperture 46 in the diaphragm 39, a passageway 44 in the casing 33, an aperture in the gasket 34 and a passageway 45 in the body 20.

An annular float 47 is pivotally mounted in a central chamber 48 of the cup-shaped casing 33 by means of a pin 49 on a depending flange 50 secured to the body 20. A tubular valve housing 52 is threaded into an opening 53 in the body 20 having an inner end portion bottomed against the end wall of the opening 53 with a gasket 54 therebetween. The tubular housing 52 has a central chamber 55 with a restricted orifice 56 at one end. The orifice 56 is in alignment with a central passage in the gasket 54 and a passage 57 in the body 20 affording communication between the chamber 55 and a tubular passage 59 connected to a source of anti-detonant fuel.

A valve 60 is slidably disposed in the chamber 55 and has a conical seating surface movable into the restricted orifice 56 and coacting with the edges thereof to control flow of fluid through the housing into the float chamber 48. An arm 75

61 of the float 47 acts on the lower end of the valve 60 to move the conical seating surface of the valve into the orifice 56 to stop the flow of fluid into the chamber 48 when the fluid in the chamber is at the desired level.

A lower boss 63 depending from the body portion 20 extends downwardly into the float chamber 48 and has a central bore or passage 64 in communication with a central passage 65 of substantially larger diameter in an upper boss 66 of the body 20 which extends upwardly in an upper boss 66 of the body 20 which extends upwardly into the vacuum chamber 27. The lower boss 63 terminates in an internally threaded portion 38 arranged to receive the threaded lower end of a tubular vent member 69 which is centrally disposed in the passage 64 and has a central bore 70. A spacer ring 71 is disposed about the tubular member 69 at the upper end thereof where the passage 64 merges with the larger passage 65 of the upper boss 66. It will thus be seen that the lower end of the passage 65 forms a discharge chamber for fluid leaving the passage 70. A passage 72 is provided in the body 20 establishing communication between the passage 65 and the passage 13 in the block 11.

An annular shoulder 73 extends downwardly from the spacer ring 71 between the tubular member 69 and the outer wall of the central passage 64 in the lower boss 63 providing an annular passage 74 which is in communication with that portion of the float chamber above the shut-off position of the float by means of a slanted passage 75. This upper portion of the float chamber 48 is vented to atmosphere through an opening 76 in the body 20.

To establish communication between the annular passage 74 and the central passage 70 of the tubular member 69 there is provided a series of radially extending passages 78 in the tubular member 69. The passageway at the center of the tubular member 69 is also in communication with the liquid in the float chamber 48 through a restricted passageway or orifice 79 in the threaded end of the tube 69.

Liquid in the float chamber 48 will, of course, pass upwardly through the passageway 79 into the central portion of the tubular passage 69 and stand at a height therein corresponding to the height of the liquid in the float chamber.

The metering valve of the present invention comprises an elongated central rod 84, a lower pointed metering end portion 85 cooperating with the restricted orifice 79, and an upper end portion 86 which is secured in the lower end of a cylindrical sliding block 88 which is slidably disposed in the opening 65 in the upper boss 66.

The central portion of the diaphragm 24 is held between washers 89 and 90 on a shoulder 91 of the block 88 by means of a peened-over end 92. Thus, flexing movement of the diaphragm 24 will cause the cylindrical block 88 to slide up and down in the central passage 65 in the boss 66 and move the pointed valve seating portion 85 toward or away from the edges of the restricted orifice 79.

The block 88 has a conical shaped lower end 88a coacting with the upper edges of the hole in the spacer ring 71 as shown in Figure 2 to act as a shut-off valve, since the pointed end 85 of the rod 84 is merely a metering valve which does not afford a positive shut-off.

The cylindrical block 88 has a central passage 89 in its upper portion which communicates with a radial passage 95 which is in communication

with an annular groove 96 on the outer periphery of the block 88. It will, of course, be recognized that should the peripheral surfaces of the valve block 88 or the surfaces of the upstanding boss 66 become worn so that liquid can pass up between the boss 66 and the block 88, the suction pressure in the chamber 27 caused by the connection of the chamber 29 with the intake manifold of the engine through the tubular member 29 would cause liquid to be drawn up through these slight openings into the vacuum chamber 27. However, since the annular groove 96 is vented to atmosphere through the passage 89 and the vented chamber 25, the effect of the vacuum between the surfaces of the body 88 and the boss 66 is broken at this point. Therefore, the vacuum will not be effective to draw liquid up past these surfaces.

A pair of concentric coil springs 93 and 94 are disposed in the vacuum chamber 27 between the main body 28 and the lower washer member 89. It is to be noted that the outer spring member 94 extends the entire distance between the washer 89 which carries the diaphragm 24 and the body 28 while the inner and heavier spring 93 does not extend all the way between these surfaces.

Downward movement of the diaphragm 24 and the associated cylindrical block 88 is effected by suction pressure in the intake manifold through the tube 29 which communicates the chamber 27 with the intake manifold 32. The springs 93 and 94 resist the downward movement of the diaphragm and are strong enough to overcome the pull on the diaphragm 24 when there is low vacuum in the intake manifold, thus permitting anti-detonant fluid to be drawn through the restricted orifice 79 and the passage 13 into the fuel intake passage of the engine. Under conditions of high vacuum, the springs permit the diaphragm to be progressively pulled down until the conical end 88a of the block 88 is seated on the top edge of the hole in the spacer ring 11, thus shutting off the supply of anti-detonant fluid. Prior to a full seating of the end 88a, however, the metering valve 85 will progressively diminish the flow.

The lower diaphragm 39 which is disposed between the fluid storage chamber 41 and the lower vacuum chamber 42 is arranged to flex against the compression of a spring 97 when the vacuum in the chamber 42 is increased. The diaphragm has a central portion comprising two oppositely disposed washer members 98 and 99 and a depending stop member 100 which is arranged to abut the cover 37 and limit the downward movement of the diaphragm.

As the diaphragm 39 is flexed against the action of the spring, fluid enters the storage chamber 41 through a ball check valve assembly including a cap member 102 with a restricted orifice 103, a ball member 104 and a stop pin 105 which restricts the movement of the ball 104 away from the orifice 103. When the ball moves away from the orifice 103 fluid will flow into the storage chamber 41. A passage 106 in the body portion 33 communicates the storage chamber 41 with a passage 107 which is in communication with the passageway 14 in the flange portion 11 and a passageway 108 in the body 20. A ball check valve assembly is disposed between the passages 106 and 107 and comprises a sleeve valve body 109 having an orifice 110 at one end thereof and a limit bar 111 disposed across the central passageway of the valve body. A ball member 112 is arranged in the passage to move between the port 110 and the stop 111 to permit

fluid to flow from the storage chamber 41 to the nozzle 16 and then into the intake of the engine.

In operation, when the engine attains a high vacuum running condition the diaphragm 39 will be flexed against the compression of the spring 97 and fluid will be stored in the chamber above the diaphragm. This condition is indicated in Figure 2 where the throttle valve 18 is partly open. Then, when a sudden low vacuum condition arises in the intake manifold, as, for example, when the valve 18 is suddenly moved to the wide open position of Figure 1, the spring will suddenly overcome the vacuum pressure in the chamber 42 and flex the diaphragm to compress the fluid in the storage chamber 41 and propel a jet of fluid through the passages 106, 107, 108 and 14 and through the nozzle 16 into the carburetor.

From the foregoing description it is seen that there is provided in this invention a supplementary fuel feed device including a flexible diaphragm which is moved to a spring-loaded position by a high vacuum running condition of the engine and which is released for ejecting a predetermined quantity of fluid into the fuel intake of the engine in response to a sudden low vacuum condition of the engine. By employing springs 97 of varying load characteristics the pressure at which this supplementary jet of fuel is injected into the carburetor can be regulated. Further, by using a variable stop device 100, the amount of liquid which would be drawn into the supply chamber 41 can be controlled as well as the length of the stroke of the diaphragm in response to the action of the spring. Thus, there is provided in this invention means for regulating the quantity of fuel injected by this supplementary fuel feed device and the pressure conditions at which it will be injected.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A device for feeding fluid to the fuel intake of a combustion engine comprising a housing defining a float chamber and having upper and lower substantially central bosses, aligned top and bottom bores extending through said bosses, a restricted orifice in said bottom bore, said top bore providing a discharge chamber at the upper end of said bottom bore, said housing having a discharge passageway in communication at one end with the fuel intake of the engine and the other end in communication with said discharge chamber, said housing having a first diaphragm-covered vacuum chamber subjected to engine manifold vacuum, a block connected to said first diaphragm and slidably in said top bore, said block having an end seatable against the top of said bottom bore to close the bore and an extension coacting with said orifice for metering flow to said end, spring means tending to move said block for increasing the area of said orifice, said spring means being disposed in said vacuum chamber and effective during initial movement of said diaphragm to provide a spring rate for increasing flow of fluid to the discharge passage, a second vacuum chamber subjected to engine manifold vacuum through said first vacuum chamber, a diaphragm disposed in said second chamber, a spring in said second chamber re-

sisting the movement of said diaphragm as the vacuum increases in said second chamber, a compartment in said housing above said second chamber in flow communication with said float chamber and with the intake of said engine, one-way flow valve means between said float chamber and said compartment for filling of said compartment during flexing movement of said diaphragm against the action of said spring in response to an increase of vacuum and for preventing discharge from said compartment to said float chamber, and additional valve means for accommodation of discharge of fluid from said compartment to the engine intake when a decrease in manifold pressure accommodates flexing of the diaphragm under the influence of the compressed spring.

2. A supplementary fuel feed device for a carburetor including a side mounting block having passages extending to the carburetor venturi, comprising: a housing arranged for attachment to the side mounting block and having a main fuel chamber; a first diaphragm secured against the upper end of said housing and defining therewith a first vacuum chamber arranged for connection to engine intake vacuum; a second diaphragm secured against the lower end of said housing and defining therewith a fuel storage chamber; a cup secured against the lower end of said housing under said second diaphragm and defining therewith a second vacuum chamber; compression spring means between said cup and said second diaphragm; said housing having a first passage establishing communication between

5
10

said first and second vacuum chambers, a second passage arranged for one-way flow from said main fuel chamber to said fuel storage chamber, a third passage arranged for one-way flow from said fuel storage chamber through one of the mounting block passages to the carburetor venturi, a vertical bore between said first vacuum chamber and said main fuel chamber, and a fourth passage arranged for fuel flow from an intermediate point on said bore through another of the mounting block passages to the carburetor venturi; a block affixed to said first diaphragm and slidable in the upper end of said vertical bore and arranged to prevent fuel flow through said fourth passage with high engine intake vacuums, restricted passage means at the lower extremity of said bore; and a rod affixed to said block and having a lower tapered end cooperating with said restricted passage means to meter fuel flow through said fourth passage in accordance with engine intake vacuum.

DAVID E. ANDERSON.
